corporation of New Jersey

Application December 4, 1940, Serial No. 368,430

9 Claims. (Cl. 230—31)

The present invention relates to a controlling apparatus, and more particularly it relates to an apparatus for controlling the operation of a constant speed motor driven compressor.

For satisfactory and economical results the operation of a fluid compressor should be related in some manner to the load demand. In the ordinary compressor unit, consisting of a fluid compressor driven by a variable speed motor, it is customary to regulate the operation of the unit to permit the compressor to deliver compressed fluid to the compressor receiver tank until a predetermined receiver tank (herein termed "compressor discharge") pressure is reached. Upon reaching such a pressure a device, provided on the compressor and actuated by the compressor discharge pressure, stops the discharge of fluid to the receiver tank, commonly termed "unloading" and, at the same time, the speed of the driving motor is decreased to idling speed. Thereafter, the compressor operates in this manner until the receiver pressure (the compressor discharge pressure) reaches a predetermined low pressure at which time the device operates to permit the compressor to resume the delivery of fluid under pressure to the receiver, commonly termed "reloading" and, at approximately the same time, the speed of the driving motor is accelerated to its maximum speed. Where the driving motor is a constant speed motor, such as an electric motor, the speed cannot be changed for varying load conditions.

With such an arrangement, instead of operating the motor at idling speed when the compressor is unloaded, the motor is stopped so that upon reloading of the compressor it is necessary to first restart the motor. Frequent starting and stopping of the motor, as occurs when the flow of fluid under pressure from the compressor is not sufficient to prevent unloading of the compressor but is sufficient to require reloading shortly after the compressor has been unloaded, is obviously undesirable and uneconomical.

Accordingly, it is an object of the present invention to provide a compressor unit controlling apparatus wherein the compressor may be unloaded while the compressor driving motor continues to operate.

Another object is to provide a compressor unit controlling apparatus wherein the compressor may unload and the driving motor may continue to operate when there is a predetermined fluid flow from the compressor to the load.

Still another object is to provide a compressor unit controlling apparatus wherein the compressor may be unloaded and the driving motor

stopped when the load on the compressor is light.

A further object is to provide a compressor unit controlling apparatus wherein the compressor may be operated continuously.

5 An additional object is to provide a compressor unit controlling apparatus wherein the unit may be operated continuously or the compressor may be unloaded and reloaded in accordance with variations in the compressor discharge pressure and the motor stopped, or the compressor may unload and reload while the motor continues to operate if there is a predetermined flow of fluid from the compressor to the load at the time that the compressor is unloaded.

10 15 These and other objects will be apparent from the following description and the drawing which forms a part thereof.

The drawing illustrates a diagrammatical view showing the electric circuits and the controlling apparatus of the present invention as applied to a constant speed motor driven compressor.

20 25 In the drawing is shown a fluid compressor having two cylinders 3 and 5 which receive fluid to be compressed through the conduits 7 and 9. The compressed fluid is discharged from the compressor through the discharge conduit 11 to a receiver tank 13 and a pipe 15 conveys the compressor discharge pressure fluid from the receiver tank to the load, or point of use.

30 35 The compressor is driven by a motor 17 by means of a belt 19, and the motor is energized by electric current supplied from the main lines 21, 23 and 25 by an appropriate electric circuit. The wires 27, 29 and 31, respectively connected to the main lines 21, 23 and 25, form a part of this circuit. Also, in the motor operating circuit is a switch 33 which is magnetically operated and on the main line side of the switch 33 is a manually operable switch 35.

40 45 The switch 33, which is commonly designated as a magnetic starter switch, has three terminals 37, 39 and 41, respectively connected to wires 27', 29' and 31', leading directly to the motor. Overload relays 43 and 45 are respectively connected to the terminals 37 and 41 and to the switch blades 47 and 51, while a wire 53 connects switch blade 49 to the terminal 39. Each blade 47, 49 and 51 is provided with a coating contactor 55, 57 and 59 respectively connected with the blades 36, 36' and 36'' of switch 35 by wires 61, 61' and 61'' through the fuses 63, 63' and 63''.

50 55 In order to move the blades 47, 49 and 51 against their respective contactors 55, 57 and 59, each blade is pivotally connected at 65 to a movable rod 67. The rod 67 is in turn rotatably connected by pin 69 to the bell crank 71 pivoted

at 73. Upward or downward movement of the arm 75 of the bell crank 71 will move the rod 67 to the right or left in order to open or close the switch 33. This movement is governed by the solenoid 77 which, when energized, will raise arm 75, close switch 33 and start the motor. As long as the solenoid remains energized, the motor will continue to operate but, when the solenoid becomes deenergized, the switch will open and the motor will be deenergized.

One control circuit for energizing the solenoid 77 consists of a wire 79 connected to the solenoid and the terminal 81 of the switch 83. One blade 85 of this switch is designed to contact the terminal 87, which is connected by wire 89 to the terminal 90 in wire 61''. The solenoid 77 is also connected by wire 91 to an overload interlock 93, provided to prevent overloading of the solenoid and designed to open upon a predetermined high current, and the interlock 93 is connected by wire 95 to the terminal 97 in the wire 61''.

Assuming that the switch 35 is closed and that the switch 83 is in the position where the blade 85 is in electrical contact with the terminal 87, electric current may then flow through the main line 25, wire 31, blade 36'', fuse 63'', wire 61'', terminal 90, wire 89, terminal 87, switch blade 85, terminal 81, wire 79, solenoid 77, wire 91, overload interlock 93, wire 95, terminal 97, wire 61'', fuse 63'', blade 36'', wire 29 and main line 23 to energize the solenoid.

Energization of the solenoid closes the starter switch 33 and current may then flow through the main lines 21, 23 and 25, the switch 35, starter switch 33 and wires 27', 29', and 31' to the motor to start it. As long as the switch 83 remains in this position and, assuming that there is no overload, etc., the motor will operate the compressor at constant speed and the compressor will deliver fluid under pressure to the receiver while the receiver delivers fluid to the load. This method of operation will be satisfactory so long as the load on the compressor is heavy enough to require continuous operation of the compressor. When, however, the load is light, or fluctuating, a different form of control is desirable and, for this reason, a second control circuit having two branches is employed.

One of the branch circuits includes a fluid pressure flow actuated switch and the other a fluid pressure actuated switch. In the first mentioned branch the other blade 99 of the switch 83 is adapted to contact a terminal 101. From this terminal extends a wire 103 leading to the pressure fluid flow actuated switch 105.

The flow switch 105 is secured in the pipe 15 which conveys pressure fluid from the receiver and consists of a body 107 having a seat 109 for the flapper 111. When there is a flow of fluid from the receiver through the valve, the flapper 111 is raised from its seat 109 and a cam 113 on the flapper is moved as the flapper leaves its seat. The arm 115, resting on the cam surface, will move when the cam surface is to be moved to a position permitting movement of the arm. In the upper part of the body 107 is an electric switch enclosed in an insulating casing 117. A plunger 119 extending through the lower wall of the insulated casing rests on the arm 115 and is normally urged downwardly by the electric spring contact 121.

Two terminals 123, and 125 are located on the top of the valve body 107 and are electrically connected by wires 127 and 129 with the contacts 121 and 131. When there is no flow of fluid through the valve body, the arm 115 and plunger 119 prevent the spring contact 121 from touching the contact 131 to close the circuit between terminals 123 and 125 and, consequently, preventing flow of current from wire 103 to the terminal 123. As fluid flows through the pipe 15, however, the flapper is moved from its seat and at a predetermined flow, determined by the movement of cam 113 necessary to permit the spring contact 129 to move into a position where it would bear against contact 131, the switch will close. A wire 133 from terminal 123 leads to the starter interlock 135 and wire 137 connects the starter interlock to terminal 90 thus completing this branch circuit.

The other branch of this controlling circuit consists of a wire 139 leading from terminal 125 to the pressure switch, generally indicated at 141, and is secured to the contact 143. A second contact 145 is connected by wire 147 to the terminal 87 of the switch 83. A plate switch 149 normally connects the contacts 143 and 145. Under certain conditions, as will be described herein-after, the plate switch may break this contact and prevent the flow of current between contacts 143 and 145. With this arrangement, if the blade 99 of switch 83 is closed, that is, in contact with the terminal 101, which means that blade 85 is not in contact with switch contact 87, current may flow along main line 23, wire 29, blade 36', fuse 63', wire 61', terminal 97, wire 95, overload relay 93, wire 91, solenoid 77, wire 79, terminal 81, blade 99, terminal 101, wire 103, terminal 125, wire 139, contact 143, plate 149, contact 145, wire 147, terminal 87, wire 89, terminal 90, wire 61'', fuse 63'', blade 36'', wire 31 and main line 25.

The closing of this circuit will also energize solenoid 77 and close starting switch 33 to initiate operation of the motor and compressor. As long as the pressure switch plate 149 closes the circuit between 143 and 145, the motor will continue to operate, but, if this circuit is broken, the solenoid will be deenergized and the motor will stop, provided that there is no flow of fluid through the pressure switch 105. If there is a flow of fluid through the pipe 15 sufficient to close the circuit in the flow switch between terminals 123 and 125 the motor will continue to operate. Thus, if the switch is closed, current may flow along the main line 25, the wire 31, blade 36'', fuse 63'', wire 61'', contact 90, wire 137, starter interlock 135, wire 133, terminal 123, wire 127, contact 131, spring contact 121, wire 129, terminal 125, wire 103, terminal 101, blade 99, terminal 81, wire 79, solenoid 77, wire 91, overload interlock 93, wire 95, terminal 97, wire 61'', fuse 63'', blade 36'', wire 29 and main line 23, thus completing the circuit between the main lines 23 and 25 and maintaining the motor in operation.

If, under such circumstances, the flow of fluid ceases, the circuit will, of course, open and the starter interlock 135 will also open. When this occurs, the motor cannot be started by a resumption of fluid flow through the flow switch and in order for the motor to be started again, the pressure switch 141 must act to complete the circuit between contacts 143 and 145. In other words, the only time that the solenoid can be re-energized and the motor restarted is when the pressure switch recloses. The pressure switch 141 in itself forms no part of the present invention.

tion and the form shown is merely by way of illustration.

As shown, the switch consists of a casing 151 in which is a valve body 153 having two valve seats 155 and 157. A valve 159 having enlarged heads 161 and 163 each provided with a tapered face to coat respectively with the valve seats 155 and 157 is slidably arranged in the valve body. A spring 165 bearing against the head 161 normally holds this head against its seat 155 and maintains head 161 off its seat 157. Above valve head 161 is a passage 167 in which the conduit 169 is threadedly secured. There is also a second passage 171 between valve seats 155 and 157 in the valve body communicating with a second conduit 173. Below the casing 151 is a diaphragm housing 175 having a passage 177 through which fluid under pressure may be introduced into the housing for actuating the diaphragm 179. The passage is connected to the receiver by the T 181 and the conduit 183. Fluid from the receiver may also be conveyed through the conduit 169 to the valve body 153 since that conduit is connected to the T 181.

When the pressure in the receiver increases, the diaphragm, being constantly subjected to the receiver pressure, tends to move upwardly and, upon a predetermined maximum compressor discharge, or receiver, pressure, the diaphragm moves sufficiently to pivot the plate 149 by means of the system of levers and springs, generally indicated at 185. The springs and levers 185 in themselves form no part of the present invention and, accordingly, are not described. At the same time, the movement of the diaphragm causes the valve 159 to rise which permits fluid under pressure to enter the valve body 153 from conduit 169 and flow past valve seat 161 to the conduit 173.

The other end of the conduit 173 is connected to the compressor unloading mechanism which is of standard construction and consists of a valve housing 187 mounted on the compressor intake. A portion of the valve housing 187 extends within the outer walls thereof and forms valve guides 189 for the cylindrical valve 191. A spring 193 normally maintains valve 191 in its open position as indicated in the drawing. In this position, fluid may enter from the atmosphere and pass around ribs 195 into the inlet pipes 7 and 9 of the compressor.

The casing 197 having a piston chamber 199 communicates with the housing 187 and contains a piston 201 adapted to transmit its motion to the projection 203 on the cylinder valve 191. Another casing 205 is secured to casing 197 and also to conduit 173. This casing has one chamber 207 opening into the piston chamber 199 and a second chamber 209 with which the conduit 173 communicates. There are two means of communication between the chambers 207 and 209, namely the orifice 211 and the port 213, both located in the wall separating the chambers. In chamber 209, between the orifice 211 and the port 213, is a ball check 215 held on the seat 217 by the spring 219. Access to the spring and ball check may be had by removing the plug 221 from the casing 205.

With this arrangement, when the receiver pressure reaches a predetermined value, the pressure valve allows fluid under pressure to flow into the conduit 171 as has been explained. Fluid then enters chamber 209 and forces the ball check 215 away from its seat 217. Raising a ball check 215 from its seat allows fluid from

chamber 209 to, not only enter chamber 207 through the orifice 211, but also through the port 213 and receiver pressure will, therefore, be present in chamber 207 to force the piston 201 and the valve 191 to the left which unloads the compressor.

Upon a decrease in the compressor discharge or receiver pressure to a predetermined minimum pressure, the diaphragm 179 moves downwardly and thus permits head 161 on valve 159 to seat and prevent the further flow of fluid under pressure through conduit 173 to the unloading mechanism. Any fluid in the conduit 173 may escape between valve head 163 and the seat 157 to atmosphere, since the head 163 is no longer resting on its seat. Meanwhile the decrease of pressure in the conduit 173 permits the higher fluid pressure present in the piston chamber 199 and chamber 207 to urge the ball check 215, with the aid of spring 219, to its seat 217 thus preventing the escape of fluid from chamber 207 through the port 213. The spring 193 then moves the valve 191 and piston 201 toward the right, but since the fluid cannot escape very fast from chamber 207, due to the restriction of the orifice 211, the valve is delayed in reloading the compressor to a certain extent so that there is a certain time delay between the time that the pressure valve acts to move the valve 159 and the time when the compressor is reloaded, depending on the size of the orifice. In this way the pressure valve may cause restarting of the motor but the compressor is not reloaded until the motor has reached its normal operating speed.

Under the practice of the present invention, therefore, it is possible to operate the compressor at constant speed continually without unloading or reloading of the compressor by closing switch 83 on terminal 87 as has been explained. Furthermore, under light fluctuating loads, the switch 83 is closed on terminal 101 and, in that event, the compressor will operate at constant speed so long as the receiver pressure does not reach a predetermined high value. When the pressure does reach the predetermined high value, the pressure switch opens the circuit between contacts 143 and 145, thus tending to stop operation of the motor unless there is a predetermined flow of fluid through the flow actuating switch 105. If there is a flow of fluid through pipe 15, the flow switch 105 maintains a circuit through the solenoid and the compressor motor continues to operate despite the fact that the compressor has been unloaded. If, for any reason, under these circumstances the flow through pipe 15 ceases, the motor will shut down and the motor cannot again be started until the pressure switch is actuated to close the circuit between contacts 143 and 145, since the starter interlock 135, which is in circuit with the flow switch 105, prevents the flow switch from starting the motor again if the flow of fluid through pipe 15 should recommence.

65 I claim:

1. In a controlling apparatus for an electric motor driven fluid compressor, the combination of an electric circuit for the motor, a normally open switch in the circuit, a solenoid to close the switch in the circuit, a first and a second electric control circuit connected to the first said electric circuit, a two position manual switch in the circuit for selecting either control circuit for energizing the solenoid, a second switch in one branch of the second control circuit, a pres-

sure responsive device adapted to open the second switch in response to a predetermined compressor discharge pressure, and a flow switch in a second branch of said second control circuit normally open adapted to close said second branch of said second control circuit upon a predetermined flow of fluid from the compressor and maintain the solenoid energized when the second switch is opened.

2. In a controlling apparatus for an electric motor driven fluid compressor, the combination of an electric circuit for the motor, a magnetically energized means in the circuit for closing the circuit to the motor, a control circuit for said means, pressure responsive means in the control circuit to deenergize the magnetic means and open said circuit upon a predetermined compressor discharge pressure, and flow actuated means in the control circuit to close the circuit upon a predetermined flow of fluid from the compressor to maintain the magnetic means energized when the pressure responsive means opens said circuit.

3. In a controlling apparatus for an electric motor driven fluid compressor, the combination of an electric circuit for the motor, a switch in the circuit, a solenoid to close the switch in the circuit, a control circuit for energizing the solenoid, a pressure responsive switch in the control circuit to open the control circuit upon a predetermined compressor discharge pressure to deenergize the solenoid, and a fluid flow actuated switch in the control circuit to maintain the control circuit closed upon a predetermined compressor discharge fluid flow to maintain the solenoid energized when the pressure control switch opens the control circuit.

4. In a controlling apparatus for an electric motor driven fluid compressor, the combination of an electric circuit for the electric motor, means in the electric circuit normally open to close the circuit to the motor, magnetic means to close the last means, a control circuit to energize the magnetic means connected to the electric circuit, pressure responsive means in the control circuit to open the circuit and deenergize the magnetic means upon a predetermined compressor discharge pressure, and a fluid flow actuated means in the control circuit to maintain the magnetic means energized upon a predetermined rate of fluid flow from the compressor when the pressure responsive means opens said control circuit.

5. In a controlling apparatus for an electric motor driven fluid compressor, the combination of an electric circuit for the electric motor, means in the electric circuit to close and open the circuit to the electric motor, magnetic means to close the last means upon energization, a control circuit connected to the electric circuit having two branches to energize the magnetic means, a two position switch in the control circuit for selecting a branch of the control circuit to energize the magnetic means, a pressure responsive means in one branch of the control circuit to open said branch circuit to deenergize the magnetic means upon a predetermined compressor discharge pressure, and a fluid flow actuated means in the other branch to maintain the magnetic means energized upon a predetermined flow of fluid from the compressor when the pressure responsive means opens said branch circuit.

6. In a controlling apparatus for an electric motor driven fluid compressor, the combination of an electric circuit for the motor, a switch nor-

mally maintaining the circuit open, a solenoid to close the switch upon energization, a first and a second control circuit for energizing the solenoid, a manual switch to selectively close either control circuit to energize the solenoid, a pressure responsive switch in the second control circuit to open said second circuit upon a predetermined compressor discharge pressure, and a flow actuated switch in said second control circuit to maintain said circuit closed to energize the solenoid upon a predetermined flow of fluid from the compressor when the pressure responsive switch opens said second control circuit.

7. In a control apparatus for an electric motor driven fluid compressor, the combination of an electric circuit for the motor, a switch normally maintaining the circuit open, a solenoid to close the switch upon energization, a first and a second control circuit for energizing the solenoid, a manually operated two contact switch having a contact in each control circuit for selectively connecting either control circuit to the electric motor circuit, a second switch in the second control circuit normally closing said circuit, a fluid pressure operated unloader for the compressor, a compressor discharge fluid pressure responsive device to open the second switch and direct compressor discharge fluid to the unloader for unloading the compressor upon a predetermined compressor discharge pressure when the second control circuit is energized, and a fluid flow actuated switch in said second control circuit to maintain the solenoid energized upon a predetermined flow of fluid from the compressor when said second switch is opened by the pressure responsive device.

8. In a control apparatus for an electric motor driven fluid compressor, the combination of an electric circuit for the motor, a switch normally maintaining the circuit open and adapted to start the motor upon closing, a solenoid to close the switch upon energization, a control circuit for energizing the solenoid, a second control circuit for energizing the solenoid, a second switch in the second control circuit normally closing the second control circuit, a fluid pressure operated unloader for the compressor, a compressor discharge fluid pressure responsive device to open the second switch and direct compressor discharge fluid to the unloader for unloading the compressor upon a predetermined compressor discharge pressure, a branch circuit in the second control circuit for energizing the solenoid, a fluid flow actuated switch in the branch circuit to maintain the solenoid energized upon a predetermined flow of fluid from the compressor when said second switch is opened, and a manually operated switch to selectively connect either control circuit to the electric motor circuit.

9. In a controlling apparatus for a motor driven fluid compressor, the combination of means to operate the motor continuously, means to operate the motor intermittently comprising means to start operation of the motor when the compressor discharge fluid pressure is less than a predetermined minimum and to stop operation of the motor upon a predetermined maximum compressor discharge fluid pressure, means to maintain operation of the motor upon a predetermined maximum discharge pressure when there is a predetermined rate of fluid flow from the compressor, and selecting means for the first and second said means.

JAMES L. DOOLEY.
